(57) **CLAIM**

The ornamental design for a surface cleaning device, as
shown and described.

DESCRIPTION

FIG. 1 is a front view of a surface cleaning device showing
the claimed design;

FIG. 2 is a rear view thereof;

FIG. 3 is a top view thereof;

FIG. 4 is a bottom view thereof;

FIG. 5 is right view thereof;

FIG. 6 is a left view thereof;

FIG. 7 is top, front left perspective view thereof;

FIG. 8 is top, front right perspective view thereof;

FIG. 9 is top, rear left perspective view thereof;

FIG. 10 is top, rear right perspective view thereof;

FIG. 11 is bottom, front left perspective view thereof;

FIG. 12 is bottom, front right perspective view thereof;

FIG. 13 is bottom, rear left perspective view thereof; and,

FIG. 14 is bottom, rear right perspective view thereof.

The broken lines in the drawings depict unclaimed subject
matter that forms no part of the claimed design.

The clean water tank located on the top front of the main
body may be transparent or solid.

The dirty water tank located on the bottom front of the main
body may be transparent or solid.
